UNITED STATES PATENT OFFICE

99,768

DESIGN FOR A LAMP SHADE

Arthur H. White, Cherrydale, Va.

Application April 15, 1936, Serial No. 62,138

Term of patent, 7 years

To all whom it may concern:

Be it known that I, Arthur H. White, a citizen of the United States, residing in Cherrydale, in the county of Arlington and State of Virginia, have invented a new, original, and ornamental Design for a Lamp Shade, of which the following is a specification, reference being had to the accompanying drawing, forming a part thereof.

I claim:

The ornamental design for a lamp shade, as shown and described.

ARTHUR H. WHITE.
